Attorney .

UNITED STATES PATENT OFFICE.

JOHN E. SORENSEN, OF LYNN, MASSACHUSETTS, ASSIGNOR TO JOHN L. SHEVENEILL
AND HELMER G. JOSEPHSON, TRUSTEES, OF MASSACHUSETTS.

SHOE SHANK.

Application filed November 29, 1926. Serial No. 151,430.

My invention relates to a metal shank adapted to be secured in the arch of a shoe during the process of manufacture and is particularly intended as an improvement on the 5 type of shank disclosed in the patent to Winchell No. 1,447,001, dated February 27, 1923. That shank comprises a piece of struck up metal arched longitudinally and provided with a groove running lengthwise thereof, but 10 terminating short of the extremity to provide flat end portions. Teeth struck up from the end portions are provided for securing the shank to the leather.

In the manufacture of turned shoes the 15 metal shank is first applied to a leather stiffener and this stiffener is inserted into the shoe, after it has been turned, and extends from the heel of the shoe to the ball line. Some means must be provided for securely holding 20 the leather shank piece and its attached metal shank in place in the shoe while it is being worn. Various means have been utilized with this end in view but none of them are as simple to apply or as securely anchor the 25 leather shank in position in the shoe as does mine.

In order that the invention may be more clearly understood, reference is had to the accompanying drawing in which:

30 Fig. 1 is a longitudinal section of a shoe showing the metal shank in position.

Fig. 2 is a plan view of the metal shank.

Fig. 3 is an elevation of Fig. 2.

Fig. 4 is a section on the line 4—4 of Fig. 3.

35 The metal shank comprises a strip of cold rolled metal having a relatively deep-groove 1, running longitudinally of the body of the shank but terminating short of the ends whereby there are provided flat end portions 2 and 3. Struck out from the end portion 2 are a pair of teeth 4 and struck out from the end portion 3 are a pair of teeth 5.

In order to prevent the shank from cutting into the overlying leather, the sides of 45 the groove 1 may be flared outwardly to provide substantial areas of contact such as, by means of flanges 6 running either partly or the whole length of the shank.

Struck out of the body of the shank along the sides and intermediate its end portions 50 are a pair of integral teeth 7.

The shank iron having already been applied to the leather shank 8 by driving the teeth 4 and 5 thereinto, the assembled piece is then placed inside the turned shoe in proper 55 position and the teeth 7 driven into and clinched on the outer sole 9. In this manner, the leather shank 8 is securely held in position against twisting or sliding in the finished shoe.

While I have disclosed the integral clinching teeth 7 in connection with the particular form of shank disclosed in the Winchell patent, it is apparent that the integral intermediate teeth could be used with modified 65 forms of the said shank.

I claim:

1. A shank iron for turn shoes comprising a strip of malleable struck up metal curved longitudinally and provided with a groove 70 terminating short of the extremities of the strip to provide flat end portions, integral teeth in the end portions adapted to be driven into and clinched in a leather shank and an integral tooth intermediate the end portions 75 adapted to be driven into and clinched in the outer sole.

2. A shank iron for turn shoes having clinching teeth in its end portions for attachment to the under side of a leather shank 80 and a pair of integral intermediate clinching teeth for attachment to the outer sole of a shoe to attach the stiffener to the sole.

3. A shank iron for turn shoes having clinching teeth in its end portions for attachment to the under side of a leather shank, the said iron being curved longitudinally and provided with a groove terminating short of the extremities of the strip to provide flat 85 end portions, and a pair of integral clinching teeth intermediate the end portions and struck out from the side of the shank and adapted to be driven into and clinched in the outer sole.

4. A shank iron for turn shoes having clinching teeth in its end portions for attachment to the under side of a leather shank and 95

a clinching tooth intermediate the end portions for attachment to the outer sole of a shoe to attach the stiffener to the sole.

5. A shank iron for turn shoes comprising a strip of malleable struck up metal curved longitudinally and provided with a groove terminating short of the extremities of the strip to provide flat end portions, fastening

devices in the end portions adapted to be driven into a leather shank and integral clinching teeth intermediate the end portions and struck out from the side of the shank and adapted to be driven into the outer sole. 10

In testimony whereof, I have hereunto set my hand.

JOHN E. SORENSEN.
